HAIR CURLING DEVICE

Nathan L. Solomon, 343 Highview Road, Englewood, N.J.
Filed Aug. 25, 1959, Ser. No. 836,000

3 Claims. (Cl. 132—42)

This invention relates to devices used for forming curls in the hair, and particularly to hair curlers for forming page boy type curls. More particularly this invention provides a page boy curler that positively holds the ends of the strands of tresses or swatches of hair to be rolled, as the ends of the strands of hair initially contact the rolling surface of the curler, without requiring any further act of the user for holding these ends preparatory to rolling the curl.

For forming curls of this general type, it is highly desirable that a single continuous curler be provided so as to produce a more natural looking curl. Difficulty in holding the ends of the strands of hair of the swatch to be curled on the curling surface of the curler preparatory to rolling made prior art page boy type curlers unsatisfactory, since the large width of the swatch to be curled at a single time made clamping all the ends of the tress tedious and time consuming. Heretofore, prior art curlers required a separate clamping operation for holding the ends of the types to be curled in place on the curler body. The use of a large number of small curlers, while easier to initially start each curl due to its smaller length, does not produce a natural looking curl, which, of course, is the desired result of the curling operation.

It is therefore an object of the present invention to provide a hair curling device for forming page boy type curls having a relatively large diameter that positively holds and maintains the ends of the strands of hair initially placed thereon preparatory to rolling, independent of any further acts of the user.

It is a further object of the present invention to provide a hair curling device that holds the ends of a tress of relatively wide width which is to be wound thereon whenever placed on the curler surface for producing a neat inwardly or outwardly directed arcuate shaped curl.

Another object of the present invention is to provide a hair curling device of relatively simple construction having an elongated cylindrical body adapted to spread the strands of hair of the tress to be curled over the body portion of the curler upon being rolled thereon and maintain the strands of hair in this spread position during use so as to produce a natural looking inwardly or outwardly directed arcuate shaped curl.

Still another object is to provide a single, continuous hair curling device for producing a page boy type curl which the self user can easily use to roll curls of various thickness.

A still further object of the invention is to provide a hair curling device that accomplishes all of the above yet is simple for self-use, inexpensive to fabricate, light weight and allows free evaporation of any moisture in the hair.

Other objects and features of the invention will be apparent when the following description is considered in connection with the annexed drawings in which:

FIGURE 1 is a front elevational view, partly broken away, of a curling device in accordance with the present invention illustrating a typical shape for conforming to the back of the head of the user;

FIGURE 2 is a front elevational view of one embodiment of a brush segment used in the device shown in FIGURE 1;

FIGURE 3 is a sectional view along line 3—3 of FIG. 1; and

FIGURE 4 shows the ends of hair of a typical tress to be curled initially engaging the body of a further embodiment of the curling device preparatory to rolling the curl.

Referring now to the embodiment shown in FIGURES

2

1—3, there is shown a curling device having an elongated continuous, generally cylindrical body member 11. Body member 11 has for its curl support surface a spirally or helically wound coil or compression spring 13 of wire or other resilient material in the desired length and defining the desired diameter and forming an elongated flexible, hollow, foraminous member that is substantially circular in cross-section. On the outer surface of spring 13 is juxtaposed a resilient, open mesh netting 16 which may be made of any convenient material such as cotton, synthetic horse hair or plastic. Both ends of coil 13 are preferably given return bends 14 inwardly as best seen in FIG. 1 to prevent the ends of the coils 13 from hooking in the hair. Netting 16 extends over both ends of wire 13 for protecting against any sharp projections and for retaining coiled wire 13 in fixed relative position with netting 16. Netting 16 may be secured about the ends of spring 13 in any convenient manner such as by stitching or if netting 16 has some rigidity then by merely folding netting 16 about 180 degrees over the ends and tucking the folded edge of netting along the inner surface of spring 13. Disposed substantially concentrically within spring 13 are a plurality of brushes 18 in spaced, longitudinal position therein as shown in FIGURE 1. While four brushes are shown disposed within spring 13 in FIGURE 1, this is merely illustrative and any other desired number may be used taking into consideration the width and curvature of the curl desired. Each brush 18, one of which is illustratively shown in FIGURE 2, has a central support member 20 which supports a multiplicity of bristles 22 projecting from and longitudinally along the peripheral surface of support member 20. Preferably bristles 22 are evenly distributed about the entire outer peripheral surface of support member 20, and are all substantially identical in length, so that the ends of bristles 22 define a substantially cylindrical rolling surface. It is desirable that bristles 22 have a high degree of resiliency so that they will retain their shape under normal use and may be made from any suitable resilient material that is capable of withstanding the ingredients normally used in hair waving lotion. Brushes 18 are easily inserted within body member 11 due to the resilient nature of bristles 22.

Support member 20 is advantageously made from a twisted pair of metal wires or rods having crimps therein so that bristles 22 are fixedly held by the crimps. Bristle support member 20 extends from both ends of brush 18 as best shown in FIGURE 2. Bristles 22 are of a length sufficient to extend beyond the outer surface of netting 16 as seen best in FIGURES 1 and 3.

As shown in FIGURE 1, the series of brushes 18 are in spaced relation within wire loop or spring 13 and connecting the contiguous extending ends of adjacent brushes 18 are flexible couplings 26. Couplings 26 advantageously may be flexible tubing of an inner diameter such as to make a tight fit with the extending ends of bristle support member 20. As shown in FIGURE 1 contiguous ends of adjacent brushes 18 are received in respective ends of coupling 26 allowing the central portion of each coupling 26 to be free to bend or flex thereby allowing the curl support member 11 to be periodically flexed along its longitudinal length so that member 11 assumes a substantially arcuate shape upon its opposite ends being displaced from the longitudinal axis towards each other. Attached at each end of coiled wire 13 is a tie cord 30 and 31 respectively for retaining the curler in place on the head of the user. While a pair of tie cords 30 and 31 are shown, an elastic band or cord may similarly be used. Other means for retaining the curling device in place on the head of the user may be used by those skilled in the art, such as a pair of bendable arms extending from opposite ends of curl support member 11.

In the use of this device, curl support member 11 is positioned to form a substantially straight cylindrical body as indicated in FIGURE 4 and the ends of the swatch of hair to be curled, designated generally at 33, is placed on the outer peripheral surface of curl support member 11. The projecting ends of bristles 22 positively hold and maintain the ends of swatch of hair 33 in place upon initial contact therewith. The curler is then rolled axially to wind the hair thereon, and when the desired amount of hair to be rolled is on the curler, tie strings 39 and 31 are placed around the forehead of the user and connected in any convenient manner such as by a bow 36 causing the curl support surface 11 to be flexed at the ends of the adjacent brushes 18 and 40 to assume the arcuate shape shown in FIGURE 1.

As shown in FIGURE 4, brushes 40 are similar to brushes 18 described above with respect to FIGURE 1 except brushes 40 have no central or bristle support ends extending therefrom. Brushes 40 are retained in place within body member 11 by the interaction of bristles 22 with netting 16.

While two embodiments have been described other forms may be used. Body member 11 may be made from a relatively thin and interstitial shell or tube. The shell could be netted or meshed by interlacing strands of synthetic thermoplastic material for providing a relatively thin and flexible tubing and brushes 18 or 40 may be conveniently disposed within the hollow mandrel formed. Further, brushes 40 or 18 may be continuous with unitary construction such that bristle support member 20 has bristles 22 which are fixedly and outwardly mounted thereon in desired longitudinal lengths with bristle support member 20 being of substantially rigid but flexible construction, thereby allowing the portions without bristles projecting therefrom to be flex to a greater degree than bristle sections and thus assume the arcuate shape shown in FIGURE 1.

While the present embodiments were described with particular reference to the page boy type or inside roll curl it is capable of forming other types of rolls for example the outside roll which is also widely known.

Thus there has been disclosed a hair curling device having an elongated interstitial flexible hollow body with a series of flexibly coupled brushes therein for forming a light weight well ventilated flexible structure on which a curl may be formed and any moisture in the hair can evaporate freely. The present invention positively holds and maintains the ends of the swatch of hair on any portion of its rolling surface without further action of the user required thus eliminating the necessity of separate means for holding the ends of the strands of hair on the curler. Furthermore the present invention by being flexible produces a more natural curl than a series of individual rigid curlers being used since differences of tension of the hair along different parts of the length of body element 11 which naturally occur in the curling process will produce a curl which is not too regular or uniform in diameter and therefore will not look artificial.

While preferred embodiments have been described above, it will be understood that many variations thereof will be readily apparent to those skilled in the art without

departing from the spirit thereof; therefore, it is intended that the foregoing description shall be deemed illustrative only and not construed in a limiting sense, the present invention being defined solely by the appended claims.

5 What is claimed is:

1. A hair curling device comprising a spaced apart helically wound coil of resilient material, a deformable foraminous material disposed about the outer surface of said coil, means for retaining said material in fixed position with respect to said coil, a plurality of brushes concentrically disposed in longitudinal spaced relation within said coil, each of said brushes having an axially aligned central support member and resilient bristles radially extending therefrom, said bristles having ends defining a cylindrical surface of a diameter slightly greater than the outer diameter of said foraminous material so that said ends of said bristles extend through and beyond said foraminous material, said central support member of each brush extending longitudinally from contiguous ends of adjoining brushes forming brush ends so that said contiguous extending ends are coaxial and spaced apart from each other, flexible coupling means interconnecting contiguous extending brush ends and means attached to opposite ends of said coil for retaining said coil in fixed relative position on the head of the user.

2. A hair curling device comprising an elongated thin walled tubular foraminous flexible body, a plurality of brushes disposed in longitudinal spaced relation within said tubular body and coaxial thereto, each of said brushes having a longitudinally aligned central support member and resilient bristles extending therefrom, said bristles having ends defining a cylindrical surface of a diameter slightly greater than the outer diameter of said flexible body so that said ends of said bristles extend through and beyond the outer peripheral surface of said body, each of said aligned central support members of each of said brushes having ends extending beyond its respective outer transverse surface of said bristles towards an adjoining brush, flexible coupling means interconnecting adjacent of said extending ends of adjoining central support members for allowing bending movement therebetween, and means for retaining said flexible body in operative position on the head of the user.

3. A hair curling device for page boy type curls comprising an elongated tubular foraminous bendable body, a plurality of spaced apart cylindrical brushes longitudinally disposed within said body, each of said brushes having a support member and flexible connecting means coupling adjoining support members for allowing bending movement of said body between said brushes.
